[57] CLAIM

The ornamental design for an electronic missile game housing, substantially as shown and described.

DESCRIPTION

FIG. 1 is an oblique view showing the front, the left side and the top of the electronic missile game housing showing my new design;

FIG. 2 is a rear elevational view thereof;

FIG. 3 is a side elevational view thereof illustrating the side which is not visible from FIG. 1; and

FIG. 4 is a bottom plan view thereof.

FIG. 2
